Chas. C. Gile

UNITED STATES PATENT OFFICE.

VICTOR GAERTNER, OF NEW YORK, N. Y., ASSIGNOR TO CONTINENTAL SHEFFIELD SILVER CO., OF BROOKLYN, NEW YORK, A FIRM.

DESIGN FOR A BREAD-TRAY OR SIMILAR ARTICLE.

55,770.

Specification for Design.

Patented July 13, 1920.

Application filed February 20, 1920. Serial No. 360,166. Term of patent 14 years.

To all whom it may concern:

Be it known that I, VICTOR GAERTNER, a citizen of the United States, residing at New York city, in the county and State of New York, have invented a new, original, and ornamental Design for a Bread-Tray or Similar Article, of which the following is a specification, reference being had to the accompanying drawings, forming a part thereof, and in which—

Fig. 2 a side elevation of a bread tray embodying my design.

I claim:

The ornamental design for a bread tray or similar article, as shown.

VICTOR GAERTNER.
